UNITED STATES PATENT OFFICE.

JOHN F. O'CONNOR, OF CHICAGO, ILLINOIS, ASSIGNOR TO WILLIAM H. MINER, OF CHAZY, NEW YORK.

SLIDING-DOOR CHECK.

1,356,003.

Specification of Letters Patent. Patented Oct. 19, 1920.

Application filed April 3, 1919. Serial No. 287,172.

To all whom it may concern:

Be it known that I, JOHN F. O'CONNOR, a citizen of the United States, residing at Chicago, in the county of Cook and State of Illinois, have invented a certain new and useful Improvement in Sliding-Door Checks, of which the following is a full, clear, concise, and exact description, reference being had to the accompanying drawings, forming a part of this specification.

10 This invention relates to improvements in sliding door checks.

In the operation of railway baggage-cars, many accidents have occurred to the baggage-men due to the sudden and unrestricted movement of the sliding side doors to close position while the baggage-men happen to be standing in the doorway. As, of course, is well known, the baggage-man opens the 20 side door on the side of the car on which the station being approached is located and remains in the doorway, ordinarily, until the train is brought to a stop at the station. Frequently the speed of the train is suddenly varied, either while being brought to rest or while being started, with the result that the momentum of the sliding door is increased, and the same, being usually of great weight, catches the baggage-man, or 30 some part of his body, between the sliding door and the door post.

The object of my invention is to provide an inexpensive and simple arrangement capable of application to old baggage-cars 35 now in service, as well as to new ones, which will automatically and effectively prevent unintentional slamming or sudden movements of the door toward close position, while readily permitting opening 40 movements of the door.

In the drawing forming a part of this specification, Figure 1 is an inside view of a portion of a baggage-car showing my improvements in connection with a sliding side door thereof, the door being shown in closed 45 position. Fig. 2 is a horizontal sectional view taken substantially on the line 2—2 of Fig. 1. And Fig. 3 is a vertical sectional view taken substantially on the line 3—3 50 of Fig. 1.

In said drawing, the side wall of the baggage-car is indicated at 10 and in which is provided a side door opening defined by the floor or tread plate 11, side posts 12—12 and 55 lintel 13. The sliding door is indicated

generally by the reference A, and, as is customary, slides on the inner side of the car wall, the opening movement of the door being limited by any suitable means—such as a stop 14—and the closing movement by 60 a corresponding stop 15, with which the vertical edges of the door are adapted to engage. The door A is supported from a horizontally extending rail or track 16 mounted on the inner side of the car wall and above 65 the door opening. The door is provided with preferably a pair of roller brackets 17—17 carrying grooved rollers 18 that ride upon the track 16 in a well-known manner. Attention is directed to the fact that the support of the door is such that the door will tend to swing about the track 16 in a direction toward the outside of the car; in other words, the door is eccentrically hung 70 with a tendency to swing from the vertical, 75 as clearly indicated in Fig. 3, and the object for which will appear hereinafter.

To prevent sudden and unintentional closing of the door after it has been moved to a full open or part open position, I provide 80 a rack 19 on the inner face of the car wall and a corresponding coöperating rack 20 on the outer side of the door A. The racks 19 and 20 are preferably located near the bottom of the door, as shown in Figs. 1 and 85 3. The teeth 21 of the two racks are so arranged that they interlock when the door A moves to the left or to close position, as viewed in Fig. 1. The teeth will readily 90 permit the door A to be moved to the left, as viewed in Fig. 1—that is, during the opening movement. Preferably the rack 19 projects inwardly from the surface of the car wall, whereas the rack 20 affixed to the door A is counter-sunk therein.

With the construction above described, and bearing in mind the fact that the door tends to have the lower edge thereof swing outwardly, the racks 19 and 20 will automatically and uniformly engage so as to 100 prevent movement of the door A to the left, as viewed in Fig. 1, and this regardless of the position of the door A, since the racks 19 and 20 are of a length corresponding to the width of the door. Consequently, if the 105 baggage-man has left the door A partly open, or fully open, and the movement of the train is such as to induce a closing movement of the door A, the same cannot take place because of the coöperation of the 110

racks 19 and 20. In order to effect the closing movement of the door, it is merely necessary for the baggage-man to grasp the handle 22, located near the forward edge of the door, and by which he can exert a sufficient force to swing the lower edge of the door inwardly and the rack 20 thereof clear of the rack 19. The opening movement of the door, of course, is not interfered with by the racks 19 and 20.

Although I have herein shown and described what I now consider the preferred manner of carrying out the invention, the same is merely illustrative and I contemplate all changes and modifications which come within the scope of the claims appended hereto.

I claim:

1. In combination with a member having a door opening and surrounding framework and a horizontally slideable door for closing said opening, means for preventing the door from accidentally moving freely to its closed position, said means including coöperating projections on the door and framework adapted to engage and lock the door against movement toward its closed position when the door is in its normal proximity to said framework, the door being adapted for manual adjustment laterally from its said normal proximity to the framework into a position where said projections clear each other and permit free movement of the door to closed position.
2. In combination with a member having a door opening and surrounding framework and a horizontally slideable door, means for preventing the door from accidentally moving freely to its closed position, said means including a toothed rack on the framework and an opposed coöperating toothed rack on the door, the racks being adapted to automatically interlock when the door is moved toward closed position and while the door is normally supported.

3. In a baggage-car having a side door opening, the combination with a sliding door for closing said opening, of an upper door supporting track, roller supporting brackets by which said door is suspended from the track, the door being eccentrically mounted with respect to the track and adapted to have the lower edge of the door normally swing toward the outside of the car, and coöperating projections on the door and wall of the car adapted to engage and lock the door against movement in a closing direction when the door is suspended in its normal eccentric position, the door being adapted for manual adjustment laterally to a position where the said projections are clear of each other to thereby permit the door to be freely moved to closed position.

4. In a baggage-car having a side door opening, the combination with a sliding door for closing said opening, of an upper door supporting track, roller supporting brackets by which said door is suspended from the track, the door being eccentrically mounted with respect to the track and adapted to have the lower edge of the door normally swing toward the outside of the car, and coöperating projections on the door and wall of the car adapted to engage and lock the door against movement in a closing direction when the door is suspended in its normal eccentric position, the door being adapted for manual adjustment laterally to a position where the said projections are clear of each other to thereby permit the door to be freely moved to closed position, said coöperating projections comprising two racks mounted respectively on the car wall and door near the bottom of the latter.

In witness that I claim the foregoing I have hereunto subscribed my name this 15th day of Mar. 1919.

JOHN F. O'CONNOR.
